UNITED STATES PATENT OFFICE

ALEXANDER CALDWELL, OF NEW YORK, N. Y.

GAS-REGULATOR.

SPECIFICATION forming part of Letters Patent No. 340,696, dated April 27, 1886.

Application filed March 11, 1886. Serial No. 194,901. (No model.)

To all whom it may concern:

Be it known that I, ALEXANDER CALDWELL, of the city, county, and State of New York, have invented a new and useful Improvement 5 in Gas-Regulators; and I do hereby declare that the following is a full and exact description thereof, reference being had to the accompanying drawings, and to the letters of reference marked thereon, making a part of 10 this specification, in which—

Figure 1 is a diametric section of my improved gas-regulator in line *w w* of Fig. 2, illustrating the device in operation. Fig. 2 is a cross-section in line *x x* of Fig. 1, illustrating 15 the device with the sponge removed and the plug screwed down to its full extent to serve as a stop valve. Fig. 3 is a cross-section in line *y y* of Fig. 1, illustrating the retaining-bars introduced to confine the sponge within 20 the regulating-chamber. Fig. 4 is a section on line *z z* of Fig. 2, and Fig. 5 is a sectional view of the device when constructed with an enlarged regulating-chamber and with the plug wholly inclosed therein.

25 My invention relates to that class of gas-pressure regulators in which the flow of gas is checked and retarded more or less in its passage to the burners by frictional devices, and has for its object to furnish a simple device 30 for the purpose at a low cost.

My invention consists, mainly, in the combination, with the gas-supply pipe, of a sponge or other equivalent cellular or fibrous body placed in the pipe and a weight or screw 35 pressing down upon the sponge to close and condense the same more or less, in proportion to the pressure of the gas in the pipe, so as to properly retard its flow through the sponge.

In the accompanying drawings, A represents a casing of metal encircling a cylindrical chamber, B, whose internal diameter exceeds the external diameter of the pipes C C, through which the supply of gas to be regulated is delivered. This casing is formed with 40 threaded openings D D at or near the bottom of the chamber B, into which the ends of the gas-pipes C C may be screwed at right angles to the length of the chamber, (see Fig. 1,) so as to include the lower end of said chamber in 45 the conduit formed by said pipes.

The chamber B is internally threaded, and a threaded plug, E, is fitted to screw down

therein, as shown in Fig. 2, the plug being made long enough to completely cover and close the openings D D when screwed fully 55 down into the chamber. The top of the chamber is closed by a cap, F, screwing down tightly thereon, and is made gas tight by a suitable gasket, G, interposed in the joint. The upper end of the screw-plug E is extended 60 in the form of a stem, E', which is carried through a gland or stuffing-box, H, formed centrally in the cap F, and terminates in a milled head or thumb-piece, I, by means whereof the screw-plug may be turned up or 65 down in its chamber.

K K (see Fig. 3) represent cross-bars, which are inserted in the openings for the pipes C C before the latter are screwed up 70 therein.

L, Fig. 1, is a sponge placed within the chamber under the plug E, so as to completely fill the space therein between the two pipes C C; or, as an equivalent for the sponge, a body 75 of cotton, wool, or other elastic, cellular, or fibrous material may be inserted in the chamber to retard the flow of gas.

Instead of forming or fitting the plug E with a stem, E', to extend out through a gland, H, it may simply be formed with a lug or head, 80 M, to be completely inclosed within the chamber, as shown in Fig. 5, and I contemplate also dispensing entirely with the threads upon the plug and allowing the same to bear upon the sponge with the pressure due to its weight 85 or to a spring interposed between its upper end and the top of the chamber, or by otherwise making it fit so closely as to permit of its retaining its position when pressed down to the required extent by mere frictional contact 90 with the sides of the chamber.

The cellular body of the sponge L or equivalent material will not only serve to retard more or less, as required, the flow of the gas, but will operate as a filter to arrest impurities therein.

In the use of my device the regulator is connected on each side with the service-pipes C C, so as to form in connection therewith a continuous conduit. A body of sponge or other 100 equivalent cellular or fibrous material, L, is then placed within the chamber between the ends of the pipes C C, and is compressed by screwing or forcing down the plug E upon the

sponge until the flow of gas at the burners is so regulated as to prevent an undue escape thereof in excess of the amount required to produce a proper degree of illumination, and which may be properly consumed at the burner.

When the sponge becomes choked, it may be readily removed and replaced by a fresh charge, and its density at any time is easily regulated to control and adjust the flow of gas through it by a movement of the plug E.

When it is desired to cut off wholly the supply of gas, it may be done by removing the charge of sponge and forcing the plug down completely in its seat, as shown in Fig. 2.

I claim as my invention—

1. The combination, with a pipe or conduit for gas and a plug traversing the opening therein, of a cellular or fibrous mass inter-

posed and confined in said conduit under the plug, substantially in the manner and for the purpose herein described.

2. A gas-tight sponge-receptacle provided with openings for connection with gas-pipes, in combination with a plug fitted in said receptacle to traverse said openings and a body of cellular or fibrous material interposed between the openings and under the plug, substantially in the manner and for the purpose herein described.

In testimony whereof I have signed my name to this specification in the presence of two subscribing witnesses.

ALEXANDER CALDWELL.
